UNITED STATES PATENT OFFICE.

CARMI O. BENTON, OF GRAINFIELD, KANSAS.

RAILWAY-TIE.

1,033,522.

Specification of Letters Patent. Patented July 23, 1912.

Application filed September 9, 1910. Serial No. 581,126.

To all whom it may concern:

Be it known that I, CARMY O. BENTON, a citizen of the United States, residing at Grainfield, in the county of Gove, State of Kansas, have invented certain new and useful Improvements in Railway-Ties; and I do hereby declare the following to be a full, clear, and exact description of the invention, such as will enable others skilled in the art 10 to which it appertains to make and use the same.

This invention relates to railway ties and has for an object to provide a tie that will be sufficiently elastic to yield under the 15 weight of passing trains, and will have novel means for limiting the yielding movement of the tie so as to prevent injury to the tie under severe conditions of service.

In the accompanying drawings, forming 20 part of this specification:—Figure 1 is a side elevation of a railway tie constructed in accordance with my invention. Fig. 2 is a cross sectional view taken on the line 2—2, Fig. 1. Fig. 3 is a top plan view of the tie. 25 Fig. 4 is a longitudinal sectional view taken on the line 4—4, Fig. 3. Fig. 5 is a cross sectional view taken on the line 5—5, Fig. 1.

The railway tie comprises a pair of superposed oppositely turned channel members 30 10 and 11 the upper member being adapted to telescope into the lower member. The lower or base member is designed to be embedded in the ballast of the road bed and the upper or head member supports the 35 traffic rails on its web.

Arranged adjacent the opposite ends of the head member are pairs of spaced angular clamps 12, these clamps being arranged upon 40 opposite sides of the traffic rail and having their free end portions adapted to be engaged over the rail base flange and having their body portions provided with openings 13 which register with threaded openings 14 formed in the head member, these openings 45 receiving the oppositely threaded ends of a stud 15, a nut 16 being threaded on that end of the stud which projects through the opening 13 in the clamp and retaining the clamp in position.

Seated within the base member are stiff helical springs 17, these springs being disposed to underlie the rails clamped by the rail clamps. The terminal convolutions of 55 each spring bear against the opposing faces of the base and head members and normally hold the head member in extended position,

that is to say, in its outermost position relatively to the base member. A washer 18 is disposed within the bore of the spring and bears with its outer edge against the lowermost convolution of the spring.

A bolt 19 is engaged through the central opening in the washer and through registering openings 20 formed in the base and head members, the head of the bolt being 65 countersunk in the head member opening as shown and bearing against the bottom face of the rail base flange. The threaded end of the bolt projects through the base member and is equipped with a nut 21 70 which may be advanced or retracted upon the bolt so as to vary the tension of the helical spring. The function of the washer above described is to prevent lateral displacement of the helical spring due to vibration of passing trains. It is clear that the projecting ends of the bolt and nut being disposed below the base member will gouge out a hollow in the road bed as the 75 head member is depressed against the pressure of the spring by a passing train, it being understood that where the tie is to be used in tunnels and the like where the road bed is of solid rock that suitable openings will be drilled in the rock to permit of the 80 yielding of the tie.

To limit the yielding movement of the head member so as to prevent mutilation of the tie during heavy traffic conditions, the open ends of the base member are closed 90 by caps 22, these caps fitting snugly against the end edges of the head member and conforming in outline to the outline of the latter. Arranged upon the inner face of each cap is a strip 23, this strip being secured by bolts, rivets, or similar connectors to the cap or may be cast integral therewith if desired. This strip is arranged a slight distance below the upper edge of the cap and forms a stop against which the head member impinges under abnormally heavy traffic conditions. It is evident that when the head member is in engagement with these stops carried by the ends that the head member will be positively held against further yielding so that no parts of the tie will 100 be injured.

For securing the caps in position, angular braces 24 are provided, a pair of these braces being arranged adjacent the upper 110 edge of each cap and a pair being arranged adjacent the lower edge of each cap. One

leg of each brace is bolted as shown at 25 to the cap and the opposite leg is bolted as shown at 26 to the adjacent side wall of the base member. The caps are thus ^{re} 5 movably secured in position so as to permit of the interior of the tie being exposed when repairs are necessary.

In order that the tendency of the head member to yield abnormally under the weight of passing trains and thereby weaken the springs 17 may be minimized, the outer surfaces of the head member 11, and also the opposing inner surfaces of the base member 10, are faced and planed to a perfect fit the object of this being to cause the tie to be practically an air-tight compartment, capable of withstanding a great amount of internal and external pressure. The object of this air-tight compartment ²⁰ within the tie is to form an air-tight cushion for the head member, distributing the strain of what telescoping movement does take place evenly throughout the tie.

Under heavy traffic conditions the compartment within the tie may be partially filled with an inexpensive oil or other non-congealing substance so that the proper resisting power of the tie compression may be maintained.

What is claimed is:--

A metallic railway tie including a channel head member and channel base member, said head member being turned oppositely to and telescoping into said base member, rail supporting means on the web of said head member, spaced helical springs interposed between both members and underlying said rail supporting means, bolts engaged through the bores of said springs and terminally engaging said head and base members, loose washers on said bolts supported upon said base member and spacing the lower ends of said springs from said bolts, caps closing the ends of said base member and bearing against the end edges of said head member, and transverse cleats on the inner faces of said caps adapted to engage the underneath face of the head member web and limit telescoping movement of said head member into said base member.

In testimony whereof, I affix my signature, in presence of two witnesses.

CARMI O. BENTON.
